UNITED STATES PATENT OFFICE.

FRANK A. HERRICK, OF TOLEDO, OHIO, ASSIGNEE TO THE HERRICK MANUFACTURING COMPANY, OF TOLEDO, OHIO, A CORPORATION.

LACING-HOOK.

1,250,873.

Specification of Letters Patent. Patented Dec. 18, 1917.

Application filed March 19, 1917. Serial No. 155,639.

To all whom it may concern:

Be it known that I, FRANK A. HERRICK, a citizen of the United States, residing at Toledo, in the county of Lucas and State of Ohio, have invented certain new and useful Improvements in Lacing-Hooks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The advantages of shoe-lacing hooks as commonly employed on men's shoes are well understood, and it is well known that but for certain objections these advantages would be available for women's shoes.

These objections are that the points of the hooks catch in the edges and trimmings of skirts and petticoats and that these garments are soon frayed and damaged by frequent engagement with the hooks. Many

devices have been produced seeking to overcome these objections, but thus far the proposed devices have failed to come into general use because of their lack of stability, their complicated nature, and their initial

expense. The object of my invention is to overcome the objections and difficulties here indicated. More particularly, my invention is designed to furnish a cheap, simple and durable lacing-hook consisting of but two

parts, which hook when engaged with a shoe-lace shall present no projecting points; which when disengaged from the shoe-lace shall invariably remain open ready for the reception of the lace, and which shall not require any manipulation to prepare the hook for the reception of the lace or to release the shoe-lace.

To these ends my device consists of the construction and arrangement of parts hereinafter described, and illustrated in the accompanying drawings, in which—

Figure 1, is a front perspective view of a series of my lacing-hooks upon a shoe and engaged with shoe-laces; Fig. 2, a central vertical sectional elevation of my device in open position, ready for the reception of a shoe-lace; Fig. 3, the same with the hook secured upon a shoe and in closed position as when engaged with a shoe-lace, and Fig.

4, a front-elevation of my shoe-lace-hook, 55 detached and closed.

Like numerals indicate like parts throughout the drawings.

In the drawings, 1 is the cylindrical body or barrel of an eyelet, open at both ends, and 60 having at its upper end the usual outwardly projecting flange or rim 2. At one side the rim 2 is extended as an arm 3 which is curved outwardly, upwardly and backwardly, as at 4, and thence projects forwardly so that the end of the arm 3 overhangs the opposite side of the rim. The arm 3 is also slightly outwardly bowed transversely. The space between the tip of the arm 3 and the rim 2 constitutes a jaw 70 into which a shoe-lace may be slipped sideways, in the usual manner. Across the arm 3, near its outer extremity, is a slot 5.

Resting loosely in this slot is a flat strip of metal 6, the inner end of which is curved, 75 as at 7, to conform to the inside of the curve 4 in the arm 3. Thence forwardly the strip 6 projects in approximately a straight line, as at 8, to the bend or elbow 9 from whence the strip extends, at nearly a right angle, 80 in approximately a straight line, to its tip 10. Shoulders 6^a formed in the opposite edges of the strip 6, between the bends 7 and 9, limit the outward longitudinal movement of the strip or latch 6 through the 85 slot 5. The bend 9 is made in the metal after the strip is inserted into the opening 5, since after the bend 9 is made the strip can not be removed.

The eyelet being engaged with the leather 90 in the usual manner as illustrated in Figs. 1 and 3, the metal tongue or latch 6 is capable of two movements, viz. first, it may swing in the slot 5 as upon a pivot, and, second, it may be projected and retracted 95 longitudinally, so that when it is retracted the tip 10 will be elevated as in Fig. 2, and when it is projected the tip will rest upon the shoe at the edge of the ring 2, as in Fig. 3. 100

Assuming that two series of these shoe-lace hooks are applied to the opposed margins of a shoe-opening, as illustrated in Fig. 1, with the tips 10 turned outwardly, now, to engage a shoe-lace with the hook, the lace 105 is slipped sideways into the jaw of the hook, under the elevated tip 10 of the latch 6 and drawn inwardly in the usual manner. The

shoe-lace strikes the latch between the bends 7 and 9 which lifts the latch, causing it to slide upwardly and outwardly until the shoulders 6^a come in contact with the sides 5 of the slot 5. This movement causes the latch to tilt forwardly so that the point 10 rests against the top of the shoe while the heel of the latch, formed by the curve 7, rests snugly in and in engagement with the 10 curve 4, in the arm 3, where it is held by the pressure of the shoe-lace as well as by the clasp of the curve. It will be seen that now the extremities of the arm 3 and of the latch 6 are so guarded that they can not engage 15 any lace or other fabric which may be brought in contact with them, and that the point 10 cannot be tilted upwardly until the withdrawal of the shoe-lace causes the latch to slide inwardly and out of engagement 20 with the bend 4.

When it is desired to unlace the shoe, the lace is drawn out sidewise, in the usual manner, causing a reverse of the movements of the latch above described, the point 10 tilting upwardly, the latch sliding backwardly and the outer side of the bend 7 coming in contact with the point 7^a, at the base of the bend 4. Now a pressure in any direction upon the point 10 will not move the latch, 25 for the reason that the contact of the latch at the point 7^a and with the side of the slot 5 locks the latch against a pivotal movement without which there can be no longitudinal movement of the latch. Thus it will be seen 30 that when the shoe-lace is withdrawn the latch is invariably opened and held in open position, for it is only when the shoe-lace strikes the inner side of the curve 7 that the inner end of the latch is lifted out of contact with the point 7^a so that the latch is 35 permitted to slide outwardly and into closed position as above described.

It will be seen that by reason of the pe-

culiar and novel conformation of the arm 3 and the latch 6, all pivots or other parts save 45 the eyelet and the latch are dispensed with, and that the device is so simplified that it will stand great strain and wear without getting out of order.

Having described my invention, what I 50 claim and desire to secure by Letters Patent, is—

1. In a device of the described character, an eyelet having one side of its rim extended as an overhanging arm, there being a 55 transverse slot in said arm near its outer extremity, a metal strip extending through said slot to form a latch, said latch being pivotally and longitudinally movable in said slot and having shoulders which limit its 60 outward longitudinal movement, the inner end of said latch being at its inner end capable of engagement, in retracted position, with the base of said arm, the outer portion of said latch being capable in extended position of closing the jaw between the outer extremity of said arm and the top of the eyelet. 65

2. A lacing-hook comprising an eyelet having integral with its rim an overhanging arm, the space between the outer extremity of the arm and the top of the eyelet forming a jaw for the reception of a shoe-lace, and a latch pivotally and reciprocably movable upon said arm to open and to close 70 said jaw, and adapted to engage said arm to hold the latch in open position and to engage said arm to hold the latch in closed position. 75

In testimony whereof I affix my signature 80 in presence of two witnesses.

FRANK A. HERRICK.
